UNITED STATES PATENT OFFICE.

GEORGE EDWARD PRAGNELL, OF BROOKLYN, NEW YORK.

RHEOTOME.

SPECIFICATION forming part of Letters Patent No. 450,319, dated April 14, 1891.

Application filed April 12, 1890. Serial No. 347,601. (No model.)

To all whom it may concern:

Be it known that I, GEORGE EDWARD PRAGNELL, of Brooklyn, in the county of Kings and State of New York, have invented a certain new and useful Improvement in Rheotomes or Interrupters, of which the following is a specification.

My improvement in rheotomes or interrupters is especially applicable to electric bells. I will describe it in connection with an electric bell, and then point out the novel features in the claims.

In the accompanying drawings, Figure 1 is a front view of an electric bell provided with a rheotome or interrupter embodying my improvement. Fig. 2 is a similar view showing certain parts in different positions. Fig. 3 is a side view of the bell and its appurtenances.

Similar letters of reference designate corresponding parts in all the figures.

A designates the bell. It is mounted upon a pillar B, which extends from a base-piece C.

D designates the clapper of the bell. It is attached to the armature e of an electro-magnet E. This electro-magnet is fastened to the base-piece, and the armature is journaled in a bracket c, extending from the base-piece C, one of the bearings for the armature being made in the form of a screw c'. The bracket c is shown as arranged to one side of the electro-magnet, and the journals of the armature are represented as located between the ends of the piece of metal of which the armature is formed. Beyond the electro-magnet and bracket the piece of metal of which the armature is formed has connected to it a spring F, whereby the armature will be retracted from the magnet. This spring is shown as connected to a screw f, that passes through the pillar projecting from the base-piece, and provision is afforded for the adjustment of the screw by means of nuts f', fitted to the screw on opposite sides of the pillar.

G' G² designate binding-posts in which may be secured circuit-wires leading from an electric battery. The binding-post G' is insulated from the base-piece. From the binding-post G' a wire g', insulated from the base-piece, extends to one of the spools of the electro-magnet. The circuit passes from this spool to the other spool, and from the latter a wire g², insulated from the base-piece, extends to

a pillar g³, which is fastened to the base-piece and extends forwardly into a position adjacent to the armature of the electro-magnet. 55 As shown, the pillar is secured in place by having a screw-thread formed upon it and being passed through a hole in the base-piece, insulated from base-piece, and having nuts applied to it in front and at the back of the 60 base piece. On the forward end of this pillar a lever H is loosely mounted to oscillate in the same plane as the armature of the magnet oscillates. As shown, this lever is provided with a central hub, which fits the forward end of the pillar, and is secured in place upon the pillar by a washer h, arranged rearwardly of it and pressed forward by a spring h', and the head of a screw h², which extends over the front of the hub. The spring h' 65 causes the washer to act as a brake, which will prevent the lever from moving too freely out of any position which it may take without seriously impeding its action. The armature e is provided with a spring or strip 70 h¹⁰, and this is located in a position to contact with that end of the lever H which is the nearer to the bell. This end of the lever is turned toward the spring or strip and armature. It is not intended that any electric 75 communication shall occur between the lever and this spring or strip. Hence when the latter is made of metal it will be insulated from the armature or insulating material will be applied to the end of the lever contacting with it. In the present instance the strip is made in the form of a metal spring and is secured to the armature by a screw in combination with washers, which will insulate the strip from the armature and the 80 screw. 85

The end of the lever H which is the farther from the bell is projected toward that portion of the metal forming the armature which is beyond the fulerums or journals of the same. 95 In the present instance this is accomplished by providing the said end of the lever with a screw h³. This screw may be adjusted to project more or less, and thereby limit the oscillation of the lever and consequently the oscillation of the armature and bell-clapper. 100

It has before been explained that the wire g² extended the circuit from the binding-post G' to the pillar g³. From this pillar the cir-

cuit extends through the lever H to the projection or screw h^2 , thence to the piece of metal forming the armature of the electro-magnet, from the latter to the bracket c, and 5 thence through the base-piece to the binding-post G².

Normally the electric circuit is closed between the binding-posts G' G², because when the parts of the rheotome or interrupter are 10 not in operation the projection or screw h^3 of the lever H contacts with the metal forming the armature e, thereby completing the circuit. When a current is supplied to the binding-posts G' G², the electro-magnet will 15 attract the armature, and, by the movement of that portion of the metal forming the armature which is beyond the pivots, swing off the end of the lever H which is the farther from the bell. The lever H will in this movement 20 acquire a momentum and be carried slightly farther than the portion of the armature which is opposite the screw h^3 , and owing to this the circuit will be broken. On the breaking of the circuit the magnet becomes 25 de-energized, the armature swings away from it, and thereupon the spring or strip h^{10} , contacting with the adjacent end of the lever H, oscillates this lever back to its normal position, thereby causing the screw h^3 to again 30 contact with the piece of metal of which the armature is formed. The closing of the circuit in this manner causes a repetition of the operations described.

By my improvement I am enabled to use a 35 small current of electricity to better effect than with the ordinary rheotome or interrupter; and, moreover, I am able to employ a larger current without drawing an arc than

is possible with a rheotome or interrupter of common form.

It will be readily seen that the lever H constitutes a circuit-changer.

What I claim as my invention, and desire to secure by Letters Patent, is—

1. The combination, with a rheotome or interrupter, of an electro-magnet, an armature therefor, a strip of spring material on said armature but insulated therefrom, an electric circuit, and a lever contacting with the strip of spring material of the armature at one end 45 and having an adjustable screw at the other end contacting with the metal of which the armature is formed, substantially as specified. 50

2. The combination, in a rheotome or interrupter, of an electro-magnet, an armature 55 therefor, an electric circuit, and a circuit-changer consisting of a lever operated by the movement of the armature to open and close the circuit insulated from the armature at one end and having a yielding bearing there- 60 on and constructed at the other end to make and break electrical communication with the metal of which the armature is formed, sub- 65 stantially as specified.

3. The combination, with a rheotome or in- 65 terrupter, of an electro-magnet, an armature therefor, a strip or spring on said armature but insulated therefrom, an electric circuit, and a lever contacting with the strip or spring 70 of the armature at one end and contacting at the other end with the metal of which the armature is formed, substantially as specified.

GEORGE EDWARD PRAGNELL.
